DESIGN FOR A JEWELRY DISPLAY BOX OR THE LIKE

James R. Putnam, Prospect, Conn.

Application April 13, 1938, Serial No. 76,472

Term of patent 3½ years

To all whom it may concern:

Be it known that I, James R. Putnam, a citizen of the United States, residing at Prospect, in the county of New Haven and State of Connecticut, have invented a new, original, and ornamental Design for a Jewelry Display Box or the like, of which the following is a specification, reference being had to the accompanying drawing, forming part thereof, in which,

Fig. 1 is a perspective view of a jewelry display box or the like in closed position showing my new design; and,

Fig. 2 is a perspective view thereof in open position.

I claim:

The ornamental design for a jewelry display box or the like, as shown and described.

JAMES R. PUTNAM.
